CONTAINER WINDING APPARATUS

Carroll P. Krupp, Akron, and Courtney H. Wenger, Cuyahoga Falls, Ohio, assignors to The B. F. Goodrich Company, New York, N.Y., a corporation of New York

Filed Nov. 28, 1961, Ser. No. 155,359

4 Claims. (Cl. 242—2)

This invention pertains to the manufacture of reinforced hollow articles, and, more particularly, to the manufacture of pressure vessels reinforced with wound filamentary material.

The apparatus of this invention has particular application in the reinforcement winding of pressure vessels which are generally of cylindrical shape with hemispherical ends.

In the manufacture of pressure vessels, particularly those for aircraft and missile applications, it is not only desirable but mandatory that the vessel have a very high strength-to-weight ratio. Through the use of the present invention pressure vessels may be so reinforced with continuous filamentary material that the ultimate tensile strength of the filamentary material is utilized without the necessity for excessive layers of reinforcement material which would result in prohibitive finished weights, requiring even more undesirable additions to the airframe structure containing the vessel. The weight advantage thus gained may then be used for larger payloads or increased fuel loadings.

Although the advantages obtainable through the use of filament reinforced pressure vessels have long been recognized, they have not been fully realized due to the problems which arose in winding doubly curved surfaces such as the hemispherical ends of elongated cylindrical vessels. These surfaces are most advantageously reinforced by winding the reinforcement in a series of geodetic loops from a location at, or as near as possible to, one end or pole portion of the article to a corresponding location at or correspondingly near the opposite end of a longitudinal axis through the article. The cylindrical portions of such vessels are easily reinforced by circumferential traverse winding. It was often the case in winding the ends of the forms that as the reinforcement material, in the form of a weftless narrow web of continuous filaments, passed about the pole portions of the article it became twisted, wrinkled, or improperly crossed over upon previously laid loops in such a way that dangerous stress points were created. Such points were necessarily weak, reducing the ultimate strength of the pressure vessel.

It is an object of this invention therefore, to provide an apparatus for the application of filamentary reinforcement material to an article having hemispherical end portions in such a manner that the full ultimate strength of the material is utilized.

It is another object of this invention to provide an apparatus for winding a series of contiguous geodetic loops of filamentary reinforcement material about the hemispherical end portions of a generally cylindrical, elongated pressure vessel.

It is a further object of this invention to provide an apparatus as described in the preceding paragraph wherein means are provided to evenly index each geodetic loop, with respect to the preceding loop whereby said filamentary material is not twisted, wrinkled or unnecessarily overlapping itself.

It is a still further object of this invention to provide an apparatus as described in the preceding paragraph, wherein said apparatus includes sensing devices to actuate said indexing means as the reinforcement material passes about the poles of the end portions of the pressure vessel.

Further objects and advantages of the invention will

2

be apparent to those skilled in the art to which it pertains from the following detailed description of a presently preferred embodiment of the invention, and from the drawings forming a part of this application, in which:

5 FIG. 1 is a side elevational view of the apparatus with a portion of the winding form cut away to illustrate more clearly its mounting means;

10 FIG. 2 is an end elevational view of the apparatus as shown in FIG. 1;

15 FIG. 3 is a schematic diagram of the pneumatic indexing circuit for the apparatus;

20 FIG. 4 is a fragmentary cross-sectional view, taken along line 4—4 of FIG. 1, showing a portion of the worm drive indexing mechanism; and

25 FIG. 5 is a perspective view of the winding form with a portion of the winding thereon completed.

30 In winding rubber lined pressure vessels with the present apparatus A it is necessary to utilize a friable winding form 10, over which the lining of the pressure vessel may be placed. The winding form 10 thus serves as a firm base for the application of reinforcement material to a thin resilient lining 11 which has been shown in the drawings as formed of rubber. After the completion of the winding operation, the form 10, which is expendable, 35 may be broken into small pieces and removed from the vessel. It will be readily understood that in the winding of metal lined vessels it may not be necessary to utilize a building form as described above if the metal lining is strong enough to sustain the winding stresses. Furthermore, if dimensional stability of the form is not crucial, an inflatable form may be used.

35 To form the lengthwise loops about the form 10, filamentary material, which is preferably a weftless tape 12 composed of a series of laterally abutting strands 13 under controlled tension, is adjustably trained from stationary creels or other supply mechanisms, not shown, to the form 10 by means of adjustably positioned guide rolls as at 14. While the train of the weftless tape 12 in the region adjacent the form 10 is maintained in a fixed winding plane during machine operation, the form is revolved in the winding plane and periodically rotatably indexed about its longitudinal axis B—B so that the tape is wrapped in successive contiguous convolutions lengthwise of the form 10. Upon completion of the necessary number 40 of such lengthwise convolutions or loops, the winding form 10 may be removed from the apparatus and then rotated only about its longitudinal axis B—B to apply circumferential windings to the cylindrical portion of the winding form 10 by means of a conventional 45 "lathe wrapping" traverse mechanism which forms no part of the present invention, and for which reason is not shown or more fully described.

50 The apparatus A is mounted upon a base plate 15 which supports a vertical cylindrical member 16. Mounted near the top of member 16 are a pair of parallel, circumferentially extending flanges 17 which define a circumferential track 18. Rotatably engaged with track 18 are a plurality of rollers 19 which movably support a 55 rotatable turntable 20. Turntable 20 has an axially extending, circumferential, flange 21 to which rollers 19 are rotatably mounted. Circumferentially formed about turntable 20 is a large spur gear 22. Also mounted on base plate 15 is a motor 23 connected to a speed reducer 24. A gear 25 is mounted on the output shaft 26 of 60 reducer 24 and is in driving engagement with spur gear 22 to rotate turntable 20 about a vertical axis C—C in response to operation of the motor 23.

65 On the top of turntable 20, passing through the axis C—C and with one end extending radially beyond the edge of the table, is a plate member 27. Near each end of plate 27 is a journal bracket 28 between which is journaled a traverse adjusting screw 29 with a handwheel

30 mounted on one end thereof. Also mounted on turntable 20 and parallel to plate 27 are a pair of slide guides 31. Slideably engaged with each guide 31 is a slide member 32. Vertically mounted on each slide member 32 is a vertical trunnion support 33 having a vertically extending portion 33a and a horizontally extending portion 33b. Each support 33 is reinforced by vertical members 34 and cross braces 35. Mounted on and between portions 33b of supports 33 is a horizontal plate 36 from which depends a bracket 37. Mounted on bracket 37 is a screw follower 38 engaged with traverse screw 29. Thus, as handwheel 30 is turned, trunnion supports 33 are moved radially, with respect to turntable 20, toward or away from axis C—C.

Mounted between portions 33a of trunnion supports 33 is a shaft 39 supporting a trunnion bracket 40. On bracket 40 a bearing sleeve 41 is mounted. Pivots mounted between support portions 33a by means of pivot brackets 42 and 43 is a gear housing 44 containing a pinion gear, not shown, mounted on a rotatable shaft 45. Pivots depending from the underside of bearing sleeve 41 by means of pivot brackets 46 and 47 is a gear rack 48 which passes through housing 44 and is engaged with the aforementioned pinion gear. Thus, as a handwheel 49 which is mounted on shaft 45 is turned, the elevation of bearing sleeve 41 may be changed as needed. The sleeve 41 is so mounted that its longitudinal axis at all times intersects the axis of rotation C—C of turntable 20.

Rotatably mounted in bearing sleeve 41 is a shaft 50 having an enlarged end portion 51. A thrust bearing 51a is positioned over shaft 50 between the sleeve 41 and shaft portion 51 to relieve the friction therebetween when shaft 50 is rotated. The building form 10 is provided with a longitudinal tube 52 having an inside diameter approximately equal to, but not smaller than, the outside diameter of the shaft portion 51. Thus, the building form 10 may be mounted on the apparatus A by placing the tube 52 over shaft portion 51, and be keyed for rotation therewith by a key, as at 53.

As seen in FIG. 4, within a gear housing 54 mounted on the outer end of bearing sleeve 41, a worm gear 55 is mounted on the end of shaft 50. Journalled in the sides of the housing 54 and projecting from either side thereof is a shaft 56 on which is mounted a worm 57 engaged with the worm gear 55. Mounted on one side of housing 54 about an end portion of shaft 56 and engageable therewith is a pneumatically operated brake 58, well known in the art, and comprising a brake drum mounted on shaft 56 which may be frictionally engaged with an expandable brake tube mounted about the drum within the brake housing, none of the details of which are shown. Such a brake is manufactured by the Fawick Corporation of Cleveland, Ohio, their catalog number being ML-140A. At the other end of shaft 56 is mounted a spur gear 59. Mounted on one side of trunnion support portion 33a, adjacent spur gear 59 and coaxial with shaft 39, is a ratcheting indexing clutch 60, also well known in the art, and comprising a pawl, not shown, mounted on a crank bracket 65 for driving engagement, as bracket 65 is moved in but one direction, with a circular ratchet, not shown, mounted about a spur gear 61 which is engaged with spur gear 59. Such a clutch is also manufactured by the Fawick Corporation, their catalog number being HPI 800/400. Pivots mounted on the same side of support portion 33a is a double acting air cylinder 62 having a piston 63, the stroke of which may be adjusted. A piston rod 64 mounted on piston 63 is pivotally connected to crank bracket 65 which activates clutch 60 when it is advanced by piston rod 64 to rotate spur gear 61 and thus rotate shaft 50 and the building form 10 mounted thereon. The apparatus will be more completely understood from the following detailed description of its operation.

Taking a given winding form 10 on which the rubber lining 11 has been fabricated, the operator mounts the form on the enlarged portion 51 of shaft 50 and keys it thereto with a key 53. Handwheel 49 is turned to elevate the form 10 to bring into the same horizontal plane the point of intersection of the form 10 with the top of tube 52 at the end nearest shaft 51 and the point of intersection of the form with the bottom of tube 52 at the opposite end of the form, as shown in FIG. 1. When this is accomplished, the operator adjusts handwheel 30 to center the midpoint of longitudinal axis B—B of the form 10 on the axis of rotation C—C of the turntable 20. By a predetermined amount, depending upon the width of the tape 12, the operator adjusts the stroke of piston 63 of double-acting air cylinder 62 by means of an adjusting screw 66 which moves a displacement piston 67, which in turn changes the effective volume of cylinder 62.

Then, by means not shown, the operator adjusts the plane in which the reinforcement material 13 is trained to the form 10, and after cementing the exterior of the rubber lining 11 to adhere it to the reinforcement material 13 to be wound thereon, he fastens the end of the web 12 to the surface of the liner 11. Motor 23 is then energized by the operator and the turntable 20 begins to rotate causing the form 10 to rotate about axis C—C. As the turntable 20 is turned clockwise a pair of valve actuating cam followers 68 and 69 mounted on flange 21 sequentially contact cams 70 and 71 mounted on base plate 15. Cams 70 and 71 are spaced 180 degrees apart, and cam followers 68 and 69 are spaced from one another sufficiently to prevent their being in contact with either of the cams 70 and 71 simultaneously. The cams and cam followers are positioned on the apparatus A in such a manner however, that the lead cam follower 68 contacts each of the cams 70 and 71 just as the winding tape 12 crosses a pole of the ends of the form at each half revolution of turntable 20, and the trailing cam follower 69 contacts each of the cams 70 and 71 preferably within the period of thirty degrees of rotation of turntable 20 following their respective contact by follower 68. With reference to FIG. 3 it will be seen that cam follower 68 is the actuating member for a normally open two way valve 72, and that follower 69 is the actuating member for an identical valve 73. With cam followers 68 and 69 in their normally extended positions, air from feed line 74 passes through valves 72 and 73 to pilot air lines 75 and 76 respectively. Air from line 75 forces a piston 77 of a pilot air cylinder 78 to its position as shown in full line. Piston 77 is mounted at one end of a piston rod 79 connected to a piston 80 of a two-way, spring return valve 81. Thus, piston 80 is also held in its full line position, compressing a piston return spring 82. Valve 81 being in its open position, air from line 74 is admitted through line 83 to one side of piston 63 in air cylinder 62. In addition to charging pilot cylinder 78, air from line 75 is fed to the air brake 58 to prevent rotation of shaft 56, thereby preventing the form 10 from rotating. In a similar manner, air from line 76 charges pilot cylinder 84 holding pilot piston 85 in its full line position. Piston 85 is mounted at one end of a piston rod 86, on the other end of which is mounted a piston 87 of a two-way, spring return valve 88 which compresses a piston return spring 89. Valve 88 being in its open position, air from line 74 is allowed to pass through valve 88 and line 90 to charge the other side of piston 63 of cylinder 62.

As turntable 20 continues its rotation, cam follower 68 engages cam 70, forcing the piston rod 91 to which it is mounted and piston 92 of valve 72 to their dotted line positions, as seen in FIG. 3. Air line 75 is thus exhausted through valve 72 to exhaust line 93, thereby 75 exhausting air brake 58 to free shaft 56 and form 10

for rotation, and allowing spring 82 to move pistons 80 and 77 to their dotted line positions. Air lines 74 and 83 are thus disconnected and the air on the right side of piston 63 of cylinder 62 as viewed in FIG. 3 is exhausted through line 83 and valve 81 to exhaust line 94. Due to the sudden pressure differential on the two sides of piston 63 it is moved very rapidly to its dotted line position to partially rotate spur gear 61, its motion being transmitted through piston rod 64, crank arm 65 and indexing clutch 60. As previously described, rotation of gear 61 is transmitted to shaft 50 to partially rotate form 10 sufficiently to just abut adjacent loops of the reinforcement material 12 and prevent them fromlapping over upon themselves.

To reset cylinder 62, cam 68 of valve 72 is extended by force of a return spring 95 as it leaves cam 70, returning piston 92 to its full line position. This allows air from line 74 to again actuate air brake 58 to lock shaft 56, preventing its further rotation by action of piston 63, and to charge pilot valve 78, thereby returning piston 89 to its full line position. Air from line 74 then flows to line 83, once more building up pressure on one side of piston 63. After a slight delay for this pressure buildup, determined by the spacing of cam followers 68 and 69, cam follower 69 contacts cam 70 forcing piston rod 96 and piston 97 of valve 73 to their dotted line positions against the force of piston return spring 98. Pilot valve 84 is thus exhausted through line 72 and valve 73 to exhaust line 99. Spring 89 thus is able to force pistons 85 and 87 to their dotted line positions allowing the portion of cylinder 62 on the left side of piston 63 to be exhausted through line 90 and valve 88 to exhaust line 100. With pressure from line 83 on one side of piston 63 the piston is retracted to its position as shown in full line, ratcheting the indexing clutch 60, and causing no rotation of shaft 56. At the completion of this action, cam follower 69 leaves cam 70, allowing spring 98 to return piston 97 to its full line position and thereby allow air from line 74 to again flow in line 76 to open valve 88. Thus, air from line 74 flows through valve 88 and line 90 to cylinder 62 where it again pressurizes the left side of piston 63. At this point the circuit is completely reset for subsequent engagement of cam followers 68 and 69 with the other cam 71, at which time the above cycle is repeated to again rotatably index the form 10 about axis B-B. It will now be understood that by adjusting the position of piston 67 in cylinder 62 by means of adjusting screw 66, and consequently adjusting the volume of pressurized air available for displacement of piston 63, that the amount of indexing rotation of building form 10 may be closely regulated. Additional regulation may be accomplished by varying the sizes of gears 59 and 61.

Thus, as rotation of turntable 29 continues, the building form 10, with its rubber lining 11, is rapidly encased in a series of continuous contiguous loops of reinforcement material 12, as seen in FIG. 5, until it is completely enclosed. Depending upon the desired ultimate strength of the pressure vessel being constructed, additional layers of reinforcement may be applied by merely continuing the rotation of turntable 29 after first appropriately cementing the outer surface of the reinforcement already applied. Upon completion of the application of the reinforcement material the form 10 is removed from shaft 51, tube 52 is removed from the form, and form 10 itself is broken into sufficiently small pieces for removal from the vessel.

Although the invention has been described with reference to a preferred embodiment thereof, it will be readily apparent to those skilled in the art to which it pertains that modifications may be made in the illustrated and described mechanism without departing from the spirit and scope of the invention as defined in the appended claims.

We claim:

1. Apparatus for winding continuous filamentary material into winding components of a filament reinforced pressure vessel; comprising a circular turntable mounted on said apparatus for rotation about a vertical central axis; vertical support members movably mounted on said turntable for radial movement relative thereto; a horizontal support rod mounted on and between said support members; a bearing sleeve pivotally mounted on said support rod at right angles thereto; a support shaft rotatably journaled by said bearing sleeve; a winding form removably mounted on said support shaft; means to rotate said turntable about said central axis; means to move said vertical support members toward and away from said central axis; means to move said bearing sleeve about its pivot; driving means operable to rotate said support shaft and the winding form mounted thereon; braking means normally actuated to prevent rotation of said support shaft; means responsive to rotation of said turntable to deactivate said braking means and to operate said driving means to rotate said support shaft, and after a predetermined time to actuate said braking means to prevent further rotation of said support shaft by said driving means; and means to train said filamentary material in a horizontal plane to said winding form.

2. Apparatus for winding continuous filamentary material into winding components of a filament reinforced pressure vessel, comprising a turntable mounted on said apparatus for rotation in a horizontal plane about a vertical axis thereof; a pair of parallel vertical supports mounted on said turntable for radial movement relative thereto; a support shaft movably mounted between the upper ends of said supports for adjustable orientation with respect to said vertical axis; a winding form removably mounted on said shaft for movement therewith; means to rotate said turntable about said vertical axis; means to move said vertical supports toward and away from said vertical axis in a radial path over said turntable; means to adjust the orientation of said shaft and said form carried thereby with respect to said vertical axis; means to train said filamentary material in a horizontal plane to said winding form; resettable indexing means operable to rotate said shaft and winding form mounted thereon a preselected amount; braking means normally actuated to prevent rotation of said shaft; a pair of cams mounted on said apparatus adjacent to and on opposite sides of said turntable; fluid pressure means operable to actuate said indexing means; a first sensing means mounted on said turntable and engageable with said cams as said turntable is rotated, said sensing means operable upon each such cam engagement to deactivate said brake and to actuate said fluid pressure means in a manner causing said preselected rotation of said shaft and operable after disengagement of said cam to actuate said braking means to prevent further rotation thereof by said fluid pressure means; and a second sensing means mounted on said turntable for engagement with said cams following disengagement thereof by said first sensing means to actuate said fluid pressure means to reset said indexing means.

3. Apparatus for winding continuous filamentary material into winding components of a filament reinforced pressure vessel, comprising a turntable mounted on said apparatus for rotation in a horizontal plane about a vertical axis thereof; a pair of parallel vertical supports mounted on said turntable for radial movement relative thereto; a support shaft movably mounted between the upper ends of said supports for adjustable orientation with respect to said vertical axis; a winding form removably mounted on said shaft for movement therewith; means to rotate said turntable about said vertical axis; means to move said vertical supports toward and away from said vertical axis in a radial path over said turntable; means to adjust the orientation of said shaft and said form carried thereby with respect to said vertical

axis; means to train said filamentary material in a horizontal plane to said winding form; resettable indexing means operable to rotate said shaft and winding form mounted thereon a preselected amount; braking means normally actuated to prevent rotation of said shaft; a pair of cams mounted on said apparatus adjacent to and on opposite sides of said turntable; fluid pressure means having two portions normally pressurized to operate said indexing means; a first sensing means mounted on said turntable and engageable with said cams as said turntable is rotated, said sensing means operable upon each such cam engagement to deactivate said brake and to actuate a first portion of said fluid pressure means reducing the pressure thereof in a manner causing said preselected rotation of said shaft, and operable after disengagement of said cam to actuate said braking means to prevent further rotation thereof by said fluid pressure means; and a second sensing means mounted on said

turntable for engagement with said cams following disengagement thereof by said first sensing means to actuate a second portion of said fluid pressure means to reset said indexing means, and after disengagement of each of such cams to repressurize said fluid pressure means.

4. Apparatus as described in claim 3, wherein said sensing means are positioned on said turntable less than thirty degrees apart.
